UNITED STATES PATENT OFFICE

118,676

DESIGN FOR A BASKET

Harold N. Stoehr, Cedar Rapids, Iowa

Application October 19, 1939, Serial No. 87,736

Term of patent 7 years

To all whom it may concern:

Be it known that I, Harold N. Stoehr, a citizen of the United States, residing at Cedar Rapids, in the county of Linn and State of Iowa, have invented a new, original, and ornamental Design for a Basket, of which the following is a specification, reference being had to the accompanying drawing, forming part thereof.

The figure is a top perspective view of the basket showing my new design.

I claim:

The ornamental design for a basket, as shown.

HAROLD N. STOEHR.
